UNITED STATES PATENT OFFICE.

HENRY H. FORSYTH, OF CHICAGO, ILLINOIS, ASSIGNOR TO THE CURTAIN SUPPLY COMPANY, OF CHICAGO, ILLINOIS, A CORPORATION OF NEW JERSEY.

CURTAIN-FIXTURE.

No. 826,023.

Specification of Letters Patent.

Patented July 17, 1906.

Application filed July 13, 1901. Serial No. 68,215.

To all whom it may concern:

Be it known that I, HENRY H. FORSYTH, of Chicago, Illinois, have invented certain new and useful Improvements in Curtain-Fixtures, of which the following is a specification.

This invention relates to a curtain-fixture designed to hold the lower end of a spring-actuated curtain in any adjusted position; and it consists in the novel construction and combination of devices hereinafter described, and particularly pointed out in the claims.

The underlying principle of my invention consists in a fixture having a device which is brought into action when the curtain is released or is being raised and which is thrown out of action while the shade is being drawn down, such device exerting a restraining influence upon the upward movement of the shade, while being wholly or partially out of action when the shade is drawn down.

My invention may be embodied in a number of practical ways; but I preferably employ wheels or rollers journaled in a head carried by the shade and brake-surfaces adjacent thereto, the roller and the brake being adapted for relative bodily movement and so arranged that they are out of contact when the curtain is being drawn down, but are drawn into contact when the curtain is being raised and when it is released. To accomplish this result, the rollers may be mounted upon journals in elongated bearings and the brakes may be stationary, or the rollers may be stationary and a movable brake employed.

In my improved fixture the application and release of the brake are both automatic and are caused by the pull of the curtain-actuating spring during the upward movement of the curtain and by the neutralization or overcoming of the power of said spring when the curtain is drawn down.

In the accompanying drawings, Figure 1 is an elevation showing a fragmentary portion of a window shade or curtain and a part of the frame of a window, the curtain-stick being broken away to expose the sliding rod and spring and the head showing in elevation, the brakes being indicated by dotted lines. Fig. 2 is an edge view of one of the heads, showing the rollers and brakes. Figs. 3 and 4 show, respectively, in side elevation

and in edge view a modified construction wherein three rollers are employed in each head, two of said rollers being adapted to contact with brakes and one of the rollers being an antifriction-roller. Figs. 5 and 6 are similar views of a form of construction wherein a single roller is employed at each end of the head, the lower roller having a brake applied thereto.

In the drawings let 7 represent the shade or curtain; 8, the hollow curtain-stick; 9, a sliding rod mounted therein; 10, an outwardly-thrusting spring, and 11 the shank of the head 12. Said head is represented as being constructed hollow and of metal and is intended to carry the rollers and brake devices.

In the construction shown in Figs. 1 and 2 the rollers 13 are mounted on opposite sides of the axis of the spring 10 and near the ends of the head 12. These rollers have journals 14 mounted in elongated slots 15, which permit the rollers to have a bodily movement lengthwise of the heads. 16 represents brake shoes or blocks, which are located within the hollow of the heads below the rollers. It will be understood that the curtain is held taut by the power of the actuating-spring of the roller on which the curtain is mounted and that said actuating-spring exerts a constant tendency to roll up the curtain. The rollers 13 are so mounted in relation to the brake-surfaces that the pull of the actuating-spring of the roller when the curtain is stationary or when it is being moved upward will be sufficient to move said rollers into contact with the brake-surfaces, so that said rollers become, in effect, friction devices, which restrain the curtain and hold it in any adjusted position, and the power of the outwardly-thrusting spring will be so proportioned as to make said friction effective. In pulling down the curtain the rollers are moved away from the surfaces of the brakes, said rollers constituting antifriction-guides.

In the construction shown in Figs. 3 and 4 an additional roller 17 is employed, serving as an antifriction means, and the brake-blocks 16 are mere pins.

In the construction shown in Figs. 5 and 6 no brake is provided for the upper roller, and said roller is not bodily movable, and there-

fore constitutes an antifriction device at all times; but the necessary friction is obtained by means of a special form of brake 18, which contacts with the lower roller 19, which is likewise mounted on a fixed bearing. The 5
brake in this case is movable, being pivoted at 18^a, and one end thereof protrudes into line with the edge of the roller 19, so as to make contact with the window-frame. When 10
the curtain is drawn up with this construction, the brake 18 contacts with the surface of the roller 19, and, if preferred, these contacting surfaces may be serrated or toothed; but the brake being eccentrically pivoted 15
would under the stress of the roller-spring make such contact with the window-frame as to cause it to bind tightly upon the surface of the roller, and the latter acts as a friction device. These and other modifications are 20
within the scope of my invention.

I claim—

1. In a curtain-fixture the combination with a curtain-stick, of an elongated head mounted transversely on the end of the stick, 25
an antifriction-roller carried by the head and having both rotary and bodily movement therein, and said head having a fixed brake-surface with which the roller engages upon the upward movement of the curtain, substantially as described.
2. In a curtain-fixture the combination with a curtain-stick and the shade carrying the same, of a head carried by the stick, antifriction-rollers carried by the head, and 30
means carried by the head for preventing the rotation of a roll upon the upward movement and permitting its rotation upon the downward movement of the head.
3. In a curtain-fixture, the combination with a curtain and a stick, of a roller carried 35
by the stick adapted to bear upon a fixed part of the window and a brake adjacent to said roller, said roller and said brake having relative movement and so placed relative to each other as to be held in engagement during the upward movement of the curtain and to be automatically disengaged by the downward movement thereof, substantially as described.
4. In a curtain-fixture for spring-actuated shades, the combination with a curtain and a stick, of a roller carried by this stick adapted to contact with the window-frame, and a brake therefor, said brake being so placed as 50
to be applied by the upward pull of the curtain-actuating spring and to be automatically released upon the downward movement of the curtain, substantially as described.
5. In a curtain-fixture for spring-actuated shades, the combination with a curtain, a stick, and a head carried by this stick, of a roller journaled in the head and a fixed brake adjacent to said roller, said roller being bodily movable toward and from the brake and so 55
placed that when the curtain is raised it will

be moved into contact with the brake and when the curtain is lowered it will be released therefrom, substantially as described.

6. In a curtain-fixture for spring-actuated shades, the combination with a curtain, a stick, an elongated head and an outwardly-thrusting spring therefor, of rollers mounted in said head toward opposite ends thereof, brakes adjacent to said rollers and the latter having bodily movement toward and from 75
said brakes whereby, when the curtain is raised, the brakes are applied and when the curtain is drawn down the brakes are released, substantially as described.

7. In a curtain-fixture, for spring-actuated shades, the combination with a curtain and a curtain-stick, of heads carried thereby; said heads having slots affording elongated bearings, rollers having journals mounted in said slots and capable of both rotary and bodily movement therein, and stationary brakes carried by the heads with which the rollers contact when the curtain is released, whereby said rollers become friction devices, substantially as described.

8. In a curtain-fixture, the combination with a stick, of a head carried by the stick, antifriction means carried by the head, and means for transforming the antifriction means into friction means upon the upward movement of the head, one of said means being fixed and the other movable, and said means acting automatically to permit the free downward movement of the curtain.

9. In a curtain-holding device, the combination of a curtain and a stick, heads at the ends of the stick having slots serving as elongated bearings, rollers or wheels mounted in the slots, having rotary movement in said slots and bodily movement along said 105
slots, the heads having immovable parts adjacent to the rollers or wheels with which said rollers or wheels contact when the curtain is moving upwardly whereby they may act as friction-surfaces, substantially as described.

10. In a curtain-fixture, a spring-actuated curtain, a guideway adjacent said curtain, a shoe mounted on said curtain, a movable guiding member mounted in said shoe to engage said guideway, and means coöperating with said guiding member to automatically vary the freedom of movement of the guiding member along said guideway upon a change in the direction of movement of the fixture.

11. In a curtain-fixture, a spring-actuated curtain, a guideway adjacent said curtain, a shoe mounted on said curtain to coöperate with said guideway, a movable guiding member mounted in said shoe to engage said guideway, and means coöperating with said guiding member to automatically vary the freedom of movement of the guiding member along said guideway, as its direction of movement is changed.

12. In a curtain-fixture, a shoe comprising

a rotary guiding member to engage a guideway and be rotated thereby and means co-acting with said guiding member to automatically vary the freedom of movement of said 5 guiding member, to allow said guiding member to move more freely along said guideway in one direction than in the other direction.

13. In a curtain-fixture, a shoe to coöperate with a guideway and comprising a slot 10 formed in said shoe and a guide-roll loosely pivoted in said slot to engage said guideway and means on said shoe to be engaged by said guide-roll to allow the said guide-roll to have a greater freedom of movement along said 15 guideway in one direction than in the other direction.

14. In a curtain-fixture, a shoe to coöperate with a guideway, there being slots in said shoe, pivoted guide-rolls loosely mounted in 20 said slots to engage said guideway and means coöperating with said guide-rolls to automatically vary the freedom of movement of said guide-rolls along said guideway.

15. In a curtain-fixture, a spring-actuated 25 curtain, guideways adjacent said curtain, shoes mounted on said curtain to reciprocate with respect thereto and spring-pressed outward to coöperate with said guideways, rotary guiding members in said shoes to engage 30 said guideways and to be rotated thereby and means to contact with said guiding members to automatically vary the freedom of movement of said guiding members and to allow

them to move more freely along said guideways in one direction than in the other direction. 35

16. In a curtain-fixture, a shoe to be pressed into coöperation with a guideway, the said guideway, said shoe being provided with a grip, a guide-roll mounted in said shoe 40 to coöperate with said grip, said grip and guide-roll having relative movement, said guide-roll engaging said guideway and means whereby the roll is forced into engagement with said grip when the shoe is stationary 45 and said guide-roll being automatically disengaged from the grip on movement of said shoe along said guideway in one direction.

17. In a curtain-fixture, a curtain, shoes mounted on said curtain, means to press said 50 shoes into coöperation with guideways, the said guideways, each of said shoes being provided with a grip and a guide-roll mounted in the shoe to coöperate with said grip, said grip and coöperating guide-roll having relative movement, and means whereby said grip and guide-roll are forced together when the shoe is pressed into coöperation with said guideway, and said grip and guide-roll being 55 automatically disengaged on movement of 60 the shoe along the guideway in one direction.
